CONDENSER WINDING MACHINE

John Q. Holmes, Anderson, Ind., assignor, by
mesne assignments, to General Motors Corpora-
tion, Detroit, Mich., a corporation of Delaware

Application August 16, 1933, Serial No. 685,323

12 Claims. (Cl. 242—55)

This invention relates to apparatus for winding strips of sheet material such as the thin strips of metal foil alternating with strips of insulating material such as paper used in the manufacture 5 of electrical condensers.

It is an object of the present invention to provide a winding apparatus having a mandrel upon which condensers may be readily wound and from which wound condensers may be readily removed, 10 thus rendering obsolete the earlier practice of providing a core for each condenser and winding a condenser upon a core which either became a permanent part of the condenser or necessitated subsequent removal from the condenser. The 15 present invention is therefore an improvement upon the condenser winding machine of F. C. Kroeger et al., Patent No. 1,641,389, issued September 6, 1927, wherein the first mentioned practice was pursued.

Further objects and advantages of the present invention will be apparent from the following description, reference being had to the accompanying drawings wherein a preferred embodiment of one form of the present invention is 20 clearly shown.

In the drawings:

Figs. 1, 2, and 3 taken together constitute a side elevation of a condenser winding machine embodying the present invention.

Fig. 4 is a plan view of a portion of the winding machine.

Fig. 5 is a front view looking in the direction of arrow 5 in Fig. 4, certain parts being shown in section, the section being taken on the line 5—5 35 of Fig. 1.

Figs. 5a and 5b are fragmentary sectional views of a detail of the machine.

Fig. 6 is a sectional view taken on the line 6—6 of Fig. 2.

Fig. 7 is a sectional view taken on the line 7—7 40 of Fig. 1.

Fig. 8 is a fragmentary sectional view taken on the line 8—8 of Fig. 4.

Fig. 9 is a fragmentary sectional view taken on the line 9—9 of Fig. 4.

Fig. 10 is a fragmentary sectional view taken on the line 10—10 of Fig. 4.

Referring to the drawings, the frame of the winding machine includes a shallow box 20, provided with a door or cover 21 which has a plurality of glass windows (see Fig. 6). The box 20 therefore provides an enclosure for and supports rolls of tin foil or other metal foil and rolls of thin paper which provide the dielectric or insulation between the strips of foil included in the con-

denser. The box 20 is provided at its under surface with mounting pads 23 by means of which the box may be mounted upon a suitable horizontal support so that the parts of the machine which require control and manipulation by the operator will be conveniently accessible. This support is not shown in the drawings but is preferably any suitable table which will support the machine at a suitable distance from the floor. The box 20 with its cover 21 provides a substantially dust proof enclosure for the condenser material. Box 20 is preferably of metal such as cast iron and may be heated in any desirable manner such as by electrical resistance elements in order to assist in expelling some of the moisture 15 from the condenser paper. As this heating means is not a part of the present invention it is not disclosed. The front end of box 20 is provided with a mounting pad 24, having a finished surface against which is bolted by screws 25 a frame 20 26 for supporting the guides or chutes for the condenser material, the mandrel about which this material is wound, and the devices for reciprocating and turning the mandrel and for applying pressure to the condenser material as it is wound 25 about the mandrel.

The devices for supporting the condenser material in box 20 and for guiding this material to the outside of the box will first be described. The box 20 incloses and supports two rolls of 30 metal foil, tin or aluminum, indicated by the dot-and-dash circles 30 and 34, and six rolls of condenser paper indicated by the dot-and-dash circles 31, 32, 33, in the upper row and 35, 36 and 37 in the lower row. The strips of material which 35 are withdrawn from these supply rolls are designated by the roll reference numbers with the affix "a". For example, the strip of tin foil being withdrawn from the roll 30 is shown at 30a, the strip of paper withdrawn from the paper 40 roll 31 is shown at 31a. Each supply roll is mounted on a spindle, carrying the drum of a friction tensioning device which tends to feed the condenser material in the desired taut condition. As all of these spindles are substantially 45 alike, but one of them will be described, namely, the spindle which holds the supply roll 37, shown in section in Fig 6. The spindle 40 is supported by ball bearings 41 and 42, mounted within a sleeve 43 which is formed integrally with 50 the box 20. Spindle 40 is axially slidable in the bearings 41 and 42 and its position with respect to box 20 is controlled by a nut 44, bearing against the bearing 42 and received by the threaded portion 45 of spindle 40. A spring 46 55

which is interposed between a washer 47 and a collar 48, pinned to spindle 40, maintains nut 44 in engagement with bearing 42. It is apparent therefore that by turning nut 44, spindle 40 may be moved endwise whereby the supply roll 37 can be adjusted so that it may have the desired relation to the other supply rolls of condenser materials. Each roll of condenser material is mounted preferably on a wooden core 49. The roll 37 and the core 49 are held against a disc 50, carried by a spindle 40 with the core supported upon an annular flange 51 which lines up core 49 concentric with spindle 40. A wedge 52 which is keyed to spindle 40 but slidably longitudinally relative thereto, is maintained in clamping engagement with core 49 by a nut 53, which is received by the threaded end 54 of spindle 40. Each disc 50 is provided with an annular flange 55, the outer surface of which provides a brake drum which is frictionally engaged by a friction member 56, carried by a lever 57 which is pivotally mounted at one end upon a stud 58 (see Fig. 2), secured to the side wall of box 20. Attached to lever 57 is one end of a spring 60, having its other end attached to a link 61 which in turn is attached to a screw 62. Screw 62 is slidably up and down with respect to the top of box 20, but is prevented from turning by means of a set screw 63, having threaded engagement with a boss provided by the top of box 20, and having its inner end projecting into a groove 65 provided by screw 62. A nut 66 cooperates with the threaded upper end of screw 62, so that by turning the nut 66, screw 62 will move up and down to vary the tension of spring 60 and consequently the amount of friction produced by the engagement of member 56 with the annular flange 55. The brakes for the upper row of material supply rolls are the same as those of the lower row of supply rolls, with the exception that the brake levers are reversed in position and the links 61a are of course much shorter than the link 61, since the upper row of supply rolls is so much nearer the top of box 20. During the winding operation it is necessary to relieve the tension on the brakes by throwing the brake members 56 out of engagement with the brake drums 55. This is accomplished in one operation by depressing a foot pedal, indicated diagrammatically at 70 in Fig. 1, the pedal 70 being preferably located near the floor and attached by a link 71 to the free end of a lever arm 72 which is attached to a shaft 73, supported by bearings 74 which are attached to the side wall of box 20, as best shown in Figs. 2 and 3. Shaft 73 carries a plurality of fingers 75, each of which is adapted to engage a brake lever 57. Just below the upper row of supply roll spindles there is a similar shaft 76, carrying fingers 75, and each of the shafts 73 and 76 carries an arm 77, located adjacent the front end of box 20. These arms 77 are connected by a link 78. It is therefore apparent that downward movement of link 71 will cause all of the fingers 75 to move downwardly and to press all of the brake levers 57 downwardly so as to permit the brake drums 55 to run freely. Spring 72a (see Fig. 1) returns the link 71 into inoperative position.

The spindle 40, which supports the foil supply roll 30 is provided with means for turning it independently of the other supply roll spindles. This means includes a screw, having a knurled head 79 which is so attached to spindle 40 as to permit adjustment of nut 44. Spindle 40 may be rotated by manipulating the knurled screw

head 79 without turning nut 44, in order to move strip 30a independently of the other material. Between the rows of material supply rolls there are a number of shelves 81, 82, 83, 84, 85 and 86 which are mounted upon bolts 81a, 82a, 83a, 84a, 85a and 86a, respectively. Each bolt, such as the bolt 86a, shown in section in Fig. 6, has a head 88 bearing against an outer surface of the shelf 86, and by reason of turning down nut 89 on the screw threaded end 90, the surface 90a of the shelf 86 is clamped against a boss 91. Care is taken to locate the shelf bolts parallel to the axes of the supply roll spindles and to construct the shelves so that the guiding surface, such as the surface 86b of shelf 86 will be parallel to spindle 40. This arrangement insures that the strips of condenser material are kept parallel to one another and to the supply rolls so as to keep the material as near straight and flat as possible. It will be noted that the shelves assist in preventing dust or lint from dropping down on the strips of material as they pass from the supply rolls to the guide chutes, which will now be described.

The frame 26 supports a rod 101, carrying a chute 100, a rod 102 carrying a chute 103, a rod 105 carrying a chute 104, and a rod 106 carrying a chute 107. The front end wall of box 20 is provided with openings 108, 109, 110 and 111, permitting the chutes 100, 103, 104 and 107, respectively, to project slightly into said front wall and to be supported thereby. As will be apparent from Figs. 1 to 3 inclusive, the chute 100 guides the foil strip 30a, the chute 103 guides the three superimposed paper strips 31a, 32a and 33a, the chute 104 guides the foil strip 34a and the chute 107 guides the three superimposed paper strips 35a, 36a and 37a. The rods 101, 102, 105 and 106 are horizontally slidable across the frame 26, and are provided with adjusting nuts 112, 113, 114 and 115, respectively. Each of these nuts is threaded onto one end of the chute supporting rods and is maintained in engagement with the upper surface of a side of frame 26 by means of a spring 116 which bears against the frame 26 and a collar 117, pinned to each chute supporting rod (see Fig. 9.) Each chute is provided with a material guiding groove 118 and with mounting ears 119. Dowel pins 120 pass through these ears and through the chute supporting rod in order to locate the chute in correct relation to its shaft, and screws 120a secure the ears and chute to the supporting rod, all as shown in Fig. 9. It is obvious that by turning the adjusting nuts, the chute may be shifted to the right or to the left as viewed in Fig. 4, in order to align the condenser paper strips and to secure the proper location of the foil strips with respect to the paper. Since the chutes 100 and 104 carry foil, and the chutes 103 and 107 carry paper, these chutes are so labeled in Figs. 1 and 7 for ready reference.

The mechanism for rotating a mandrel to be described later will be dealt with presently. Frame 26 supports a stub shaft 130 upon which is mounted a gear 131, having a hub 132 to which is attached by a pin 133 the hub 134 of a combined pulley and hand-wheel 135. The gear 131 meshes with a gear 137, mounted on a shaft 138 which is carried by frame 26. Gear 137 meshes with a gear 139, mounted upon a spindle 140 which is journaled within ball bearings 141 and 142, provided by a hollow sleeve 143 which is formed integrally with the frame 26. Spindle 140 supports a mandrel driving center 145 which comprises a cylindrical bar 146, received in an annu-

lar recess 147 of spindle 140 and having one end thereof provided with a V-groove 148 which is adapted to receive the flat and tapered sides 149 and 150 of a mandrel 151. Bar 146 is normally urged toward the mandrel 151 by a compression spring 152 which is located in the annular recess 147 and bears with one end against the end of bar 146 and with the other end against the bottom of said recess. Movement of bar 146 toward or away from the mandrel 151 is kept within limits by a pin 153 which is attached to spindle 140 and extends through an oblong slot 154 of bar 143. A head 155 in ring form is drawn or pressfitted over the grooved end of bar 146 for the purpose of reinforcing this portion which is weakened by the presence of the groove and for still another purpose which will appear obvious later. The combined pulley and handwheel 135 derives motion from any suitable prime mover which is connectible with said combined pulley and handwheel by means of any conventional foot operated clutch (not shown) and a belt 156. The mandrel 151 is formed by a reduced end portion of a spindle 160 which is journaled in a sleeve 161 rotatably supported within another sleeve 162 which itself is received by a bore 163 of frame 26. Sleeve 161 is provided with a head 164, providing a race 165 for a plurality of balls 166 which also race on the end surface 167 of sleeve 162. Sleeve 161 is held longitudinally immovable relative to sleeve 162 by a retainer 168 which is threaded over the reduced end portion 169 of sleeve 162 and which maintains head 164 of sleeve 161 in permanent engagement with balls 166, and the latter in permanent engagement with the end surface 167 of sleeve 162. A cap 170, which is threaded over a reduced portion 171 of sleeve 161, surrounds the mandrel 151 and projects with its end surface 172 adjacent an end 173 of a condenser 174 which is being wound. Spindle 160 is movable longitudinally relative to sleeve 161 and rotatable with the latter by means of a pin 175, carried by said spindle and projecting into a longitudinal groove 176 of sleeve 161. Sleeve 162 is normally held in the position shown in Fig. 5 by a compression spring 177 surrounding said sleeve and bearing with one end against a spring retainer 178 which is received by the bore 163 and secured therein by a screw pin 179, and with the other end against an annular shoulder 180 of sleeve 162. A screw pin 181, which is received by bracket 26, has a pin 182, received by a longitudinal groove 183 of sleeve 162. This screw pin 182 in cooperation with the groove 183 prevents rotation of sleeve 162 relative to bracket 26, however, permits longitudinal movements of the same relative to bracket 26 within the limits defined by the length of the groove 183. In Fig. 5 the various spindles and sleeves which are necessary for the rotation and reciprocation of mandrel 151 are in winding position, and it will be observed that sleeve 162 is in end position as follows from the engagement of the screw pin 182 with an end wall of groove 183, whereas bar 146 is appreciably retracted as follows from the position of pin 153 within slot 154.

In order to wind a condenser, an operator takes hold of the various foil and paper strips which emerge from the chutes 100, 103, 104 and 107, and winds a few layers of these strips upon the mandrel by rotating the hand wheel 135 in the proper direction. After a few layers of the material are thus wound upon the mandrel, the operator actuates the already described brake release pedal 70 and at the same time actuates the referred foot clutch whereupon the mandrel 151

is power driven. After the condenser has been wound the operator disengages the foot clutch to stop further rotation of the mandrel, then separates the last layer of the condenser material from the material supply with a knife and finally glues a layer of wrapping paper to the condenser in order to prevent the condenser layers from unwrapping. Such wrapping paper may be applied in the manner disclosed in the patent to F. C. Kroeger, No. 1,641,389, issued September 6, 1927. The condenser now has to be removed from the machine to make room for the winding of another condenser. To provide for ready removal of a wound condenser from the machine, spindle 160 which carries the mandrel is moved longitudinally in the direction of arrow 180 sufficiently to clear mandrel 151 entirely from the condenser so that the same may be removed in a direction at right angles to its own axis. As best shown in Figs. 1, 4 and 5 a bracket 191 is attached by bolts 192 to a side wall of bracket 26. Attached to this bracket 191 by screws 192a is a cylinder 193 which receives a piston 194, having a piston rod 196, one end of which is guided for longitudinal movement in a sleeve bearing 197, 25 extending from and integral with bracket 191, as best shown in Fig. 1. An aperture 198 in bracket 26 is provided for the reception of the piston rod when in the position shown in Fig. 5. Piston 194 is urged into the position shown in Fig. 5 by a compression spring 199, interposed between said piston and the end wall 200 of cylinder 193. A cylinder cover 201 is secured to the cylinder by screws 202 and seals the same, providing only for the passage of the piston rod into the cylinder. Attached to the piston rod 196 by a bolt 203 is a member 204, the fork 205 of which embraces a block 206 and is secured thereto by screws 207. Block 206 is slidable longitudinally on sleeve 162. A screw pin 208, received by block 206, projects through a longitudinal slot 209 of sleeve 162 and into an annular groove 210, provided by spindle 160, so that upon axial movement of the piston and piston rod, the spindle 160 and mandrel 151 are bound to follow the piston rod by intermediation of member 204, screws 207, member 206 and screw pin 208. High pressure fluid from any suitable supply (not shown) is conducted through a conduit 211, a first valve 212, a conduit 213, a second conventional Powell blow-gun 214 which is in every detail like valve 212, and a conduit 215 which leads to an entrance duct 216 communicating with the cylinder chamber 217. Referring to Figs. 5a and 5b, there is shown valve 212. A sliding valve 211a which is provided with a push button 218 is normally urged into engagement with a valve seat 212a by means of a spring 213a, interposed between the valve body and said push button. This valve 211a normally intercepts communication between a central passage 214a which communicates with conduit 213, and a passage 215a which communicates with conduits 211. However, passage 214a is normally in communication with the atmosphere by intermediation of an annular groove 218a of the valve 211a and a communicating vent 216a in the valve body. Upon depression of the valve by an operator into the position shown in Fig. 5b against the tendency of spring 213a, fluid pressure is permitted to flow through conduit 211, 70 passage 215a past the valve seat and through passage 214a to conduit 213, whereas the vent 216a is intercepted from communication with passage 214a by the stem of the depressed valve 211a. When the operator releases valve 211a in de-

pressed position, it will normally yieldingly return to normal position. The two valves 212 and 214 are arranged in tandem fashion with the result that in order to provide communication between the fluid pressure supply and cylinder chamber 217, both valves have to be actuated simultaneously. The valves have been so spaced from each other that it is impossible for the operator to actuate the push buttons 218 with one hand. It is therefore apparent that in order to admit fluid pressure to cylinder chamber 217, the operator has to use both hands for simultaneously actuating the valves. Upon release of one of the valves by the operator the cylinder is immediately vented through the released valve as can be readily understood from the foregoing description and the compression spring 199 moves the piston and therewith the mandrel into the position shown in Fig. 5 much faster than the operator could reach the mandrel with the hand which released one of the push-buttons of the valves. It is therefore obvious that the tandem arrangement of the two valves serves for a safety purpose, namely, to prevent the operator's hand from getting caught between the head 155 and the comparatively thin mandrel 151 while the latter moves into the position shown in Fig. 5. Upon simultaneous actuation of both valves, the mandrel 151 rapidly recedes in the direction of arrow 190. During the early part of such receding movement of the mandrel, the end surface 173 of the wound condenser will strike against the end surface 172 of the cap 170, and upon continued receding movement of the mandrel the condenser will be stripped off said mandrel and finally drop vertically upon the surface 26a of bracket 26 from where it is removed. Subsequently the operator releases one or both of the push buttons 218 of the valves which results in movement of the mandrel from most retracted position into the position shown in Fig. 5, ready to receive the layers of the next condenser to be wound.

A gauge 220 is provided which indicates to the operator the increasing number of layers of material during the winding of the condenser so that the operator may stop the rotation of the mandrel at the proper time and in the earlier described manner after a predetermined number of layers of material is wound upon said mandrel. This gauge may be of any well known type and in the present instance comprises a pointer 221 rotatable about an axis 222 and driven by a worm wheel 223 which is in constant mesh with a worm 224 mounted in any suitable manner on spindle 140, as best shown in Fig. 5. Intermediate the worm wheel 223 and the pointer 221 is a stationary graduated plate 225, the graduation thereof starting with zero and representing the actual number of revolutions of the mandrel which is analogous to the number of layers of material wound thereon. After the winding of a condenser the pointer 221 is always set back into alignment with zero, ready for the winding of the next condenser.

After the initial layers of condenser are wound manually upon the mandrel 151 and before the operator connects said mandrel with the earlier mentioned power drive, he presses a metallic roller 230 against the initially wound layers of material on the mandrel so as to pack down or roll down the following layers of power wound condenser material. This metallic roller 230 which is of substantial weight is loosely mounted on a rod 231 (see Fig. 10), having reduced

threaded portions 232, which are received by notches provided in the arms 233 and 234 of levers 235 and 236, respectively. A nut 237, when tightened, causes the shoulder 238 of rod 231 to engage arm 234, and a nut 239, when tightened, causes the arm 233 to be clamped against a spacer 240 which also bears against the roller 230. Screws 241 and 242 may be turned in order to adjust the location of the rod 231 so that its axis and therewith the axis of roller 230 will be parallel with the mandrel 151 to insure that the roller bears as equally as possible upon the condenser winding material on the mandrel. In order to apply pressure to the roller 230 during the winding operation and to throw the roller into inoperative position while a condenser is being removed from the machine, there is provided a lever 243 attached to a shaft 244 which is carried by the frame 26 as best shown in Fig. 7. Shaft 244 carries hubs 245 and 246, having formed integrally therewith tubes 247 and 248, respectively, which telescope with tubes 249 and 250, respectively, having hubs 251 and 252, respectively. Adjustable screws 253 and 254 pass through the hubs 251 and 252, respectively, and have shoulders which bear against compression springs 255 and 256, located in the tubes 247 and 248, respectively. Obviously by adjusting the screws 253 and 254, the tendency of the springs 255 and 256 to separate the respective telescoping tubes, which enclose them, can be varied. The hub 251 carries studs 257 upon which are mounted axially aligned rollers 258 engaging arcuate slots 259 which, as shown in Fig. 1 are provided in each of the arms 260, forming a part 35 of lever 235. The hub 252 is also provided with studs 261 and rollers 262 which engage within arcuate slots similar to the slots 259, these slots being provided in the arms 263, forming a part 40 of lever 236. The levers 235 and 236 are pinned with their arcuate slots in alignment to a shaft 264 which is journaled in frame 26 and parallel to the mandrel 151. When the lever 243 is in the position shown in Fig. 1, the roller 230 is in position to bear against the condenser material as it is wound upon the core. This pressure will vary somewhat as the condenser increases in diameter but such variation will not adversely affect the process. The pressure exerted by roller 230 against the material on the mandrel is sufficient to tend to keep all of the wrinkles ironed out from the paper and foil as they are wound upon the mandrel, and to cause the condenser materials to be wound in compact form with air spaces or pockets reduced to a minimum. When 55 the lever 243 is rocked clockwise as viewed in Fig. 1, until it engages a stud 270, carried by frame 26, the levers 235 and 236 will be rotated counterclockwise as viewed in Fig. 1, thus causing the roller 230 to be moved into inoperative 60 position to facilitate removal of the condenser. The spring 255 will yieldingly hold the lever 243 in engagement with stud 270 because the axis of said spring will then lie to the right (as viewed in Fig. 1) of a line connecting the axes of shafts 65 244 and 264, and the spring 255 will therefore tend to rotate the levers 235 and 236 counterclockwise as viewed in Fig. 1.

While the form of embodiment of the present invention as herein disclosed, constitutes a preferred form, it is to be understood that other forms might be adopted, all coming within the scope of the claims which follow.

What is claimed is as follows:

1. In a winding machine, the combination of 75

5 a stop; an axially movable sleeve yieldingly urged into engagement with the stop; a mandrel for winding layers of material thereon, said mandrel being journaled in said sleeve and movable axially relative thereto; spring means urging the mandrel in one direction; and means for moving the mandrel in the opposite direction whereby the wound object on the mandrel engages the sleeve and tends to move the same away from the stop thereby being stripped off the mandrel.

10 2. In a winding machine, the combination of a stop; an axially movable sleeve yieldingly urged into engagement with the stop and having a longitudinal slot; a mandrel for winding layers of material thereon, said mandrel being journaled in said sleeve and movable axially relative thereto and having an annular groove; spring means urging the mandrel in one direction; and reciprocable means including a screw pin projecting through the slot of the sleeve and into the annular groove of the mandrel for moving the latter in the opposite direction whereby the wound object on the mandrel engages the sleeve and tends to move the same away from the stop thereby being stripped off the mandrel.

15 3. In a winding machine, the combination of a stop; an axially movable sleeve yieldingly urged into engagement with the stop and having a longitudinal slot; a mandrel for winding layers of material thereon, said mandrel being journaled in said sleeve and movable axially relative thereto and having an annular groove; a block slidably mounted upon the sleeve; a screw pin received by the block and projecting through the slot of the sleeve and into the annular groove of the mandrel; spring means urging the block in one direction; and means for moving the block in the opposite direction whereby the wound object on the mandrel engages the sleeve and tends to move the same away from the stop thereby being stripped off the mandrel.

20 4. In a winding machine, the combination of a stop; an axially movable sleeve yieldingly urged into engagement with the stop and having a longitudinal slot; a mandrel for winding layers of material thereon, said mandrel being journaled in said sleeve and movable axially relative thereto and having an annular groove; a block slidably mounted upon the sleeve; a screw pin received by the block and projecting through the slot of the sleeve and into the annular groove of the mandrel; a cylinder having a piston therein connected to the block for reciprocation of the latter; a spring in said cylinder urging the piston in one direction; and means for admitting fluid pressure to the cylinder so as to move the piston in the opposite direction whereby the wound object on the moving mandrel engages the sleeve and tends to move the same away from the stop thereby being stripped off the mandrel.

25 5. In a winding machine, the combination of a reciprocable mandrel for winding material thereon; means including a cylinder and a piston therein for reciprocating the mandrel; a spring in said cylinder urging the piston in one direction; and means for admitting fluid pressure to said cylinder for moving the piston in the opposite direction, said means including two manually operable valves connected in tandem fashion and spaced apart a distance greater than the expanse of a human hand; and means preventing longitudinal movement of the wound object in said opposite direction relative to the mandrel whereby the object is stripped off the mandrel.

upon movement of the latter in said opposite direction.

6. In a winding machine, the combination of a rotatable and axially reciprocable mandrel for winding material thereon; a bar in axial alignment with the mandrel and providing a driving center for the latter, said bar being movable axially within pre-assigned limits; yielding means urging the mandrel toward said bar; and yielding means urging the bar toward the mandrel.

10 7. In a winding machine, the combination of an axially reciprocable and rotatable mandrel for winding material thereon, one end of said mandrel being provided with opposite tapered flats; a driving center movable coaxially of the mandrel and being provided with a V-groove adapted to receive the flats of the mandrel; yielding means urging the driving center toward the mandrel; yielding means urging the mandrel toward the driving center; a stop; and a ring secured over the grooved end of the driving center, said ring engaging the stop when said driving center is moved by the approaching mandrel a certain distance against the tendency of the yielding means to urge said driving center toward the mandrel.

15 8. In a winding machine, the combination of a reciprocable mandrel for winding layers of material thereon; yielding stop means for preventing longitudinal movement of the wound object in one direction relative to the mandrel; and yielding means for moving the mandrel in either direction, the wound object being stripped off the mandrel upon engagement with said stop means during movement of the mandrel in said one direction.

20 9. In a winding machine, the combination of a reciprocable mandrel for winding layers of material thereon; yielding stop means for preventing longitudinal movement of the wound object in one direction relative to the mandrel; spring means urging the mandrel in the opposite direction; and fluid pressure operated means for moving the mandrel in said one direction whereby the wound object is stripped off the mandrel upon engagement with said stop means.

25 10. In a winding machine, the combination of a stop; an axially movable sleeve yieldingly urged into engagement with the stop and having a longitudinal slot; a mandrel for winding layers of material thereon, said mandrel being journaled in said sleeve and movable axially relative thereto and having an annular groove; and yielding reciprocating means including a screw pin projecting through the slot in the sleeve and into the annular groove of the mandrel for reciprocating the latter, the wound object on the mandrel engaging the sleeve and tending to move the same away from the stop during movement of the mandrel in a certain direction whereby said wound object is stripped off the mandrel.

30 11. In a winding machine, the combination of a reciprocable mandrel for winding material thereon; power operated means for moving the mandrel in one direction; yielding means urging the mandrel in the opposite direction; means for preventing longitudinal movement of the wound object in said one direction relative to the mandrel whereby the object is stripped off the mandrel upon movement of the latter in said one direction; and two manually operable controls for rendering the power operated means effective, said controls being spaced apart a distance greater than the expanse of a human hand and

being so associated with the power operated means that both controls have to be operated to render said power operated means effective.

12. In a winding machine, the combination
5 of a reciprocable mandrel for winding material thereon; power operated means for moving the mandrel in one direction; yielding means urging the mandrel in the opposite direction; means for preventing longitudinal movement of the wound
10 object in said one direction relative to the mandrel whereby the object is stripped off the man-

5
drel upon movement of the latter in said one direction; and two manually operable controls for rendering the power operated means effective, said controls normally rendering the power operated means ineffective and being spaced apart a distance greater than the expanse of a human hand and being so associated with the power operated means that both controls have to be operated to render said power operated means effective.
